UNITED STATES PATENT OFFICE.

JOHN Q. ADAMS, OF OMAHA, NEBRASKA.

DESIGN FOR A HOTEL-CABINET.

No. 38,607.

Specification for Design.

Patented June 4, 1907.

Application filed February 16, 1907. Serial No. 357,600. Term of patent 7 years.

To all whom it may concern:

Be it known that I, JOHN Q. ADAMS, a citizen of the United States, residing at Omaha, in the county of Douglas and State of Nebraska, have invented a new, original, and ornamental Design for Hotel-Cabinets, of which the following is a specification, reference being had to the accompanying drawing, forming part thereof.

Figure 1 is a front elevation of my new, original and ornamental hotel cabinet. Fig. 2 is an end elevation of the same.

I claim:

The ornamental design for a hotel cabinet as shown.

JOHN Q. ADAMS.
